TRUCK ASSEMBLY FOR MODEL RAILWAY CARS

Sigurd Beutlich, Chicago, Ill., assignor to Scale-Models, Inc., Chicago, Ill., a corporation of Illinois

Application June 16, 1937, Serial No. 148,529

4 Claims. (Cl. 46—218)

The invention relates to the construction of models of truck assemblies for model railway cars.

It is an object of the invention to produce miniature or model railway equipment which will resemble with much fidelity the exterior appearance of full-sized structures. The small scale to which these models are reproduced and the cost entailed prohibits fastening of the parts in the same manner as they are fastened in the full-sized equipments. Therefore, construction must be provided for the models which will be relatively inexpensive but will cause the assemblies to have the same general appearance as the corresponding full-sized structures.

Other objects and advantages will become apparent as the following detailed description progresses, reference being had to the accompanying drawing, wherein—

Fig. 1 is a plan view of a model truck assembly for railway cars, which model truck assembly embodies the invention.

Fig. 2 is a side elevation of the improved model truck assembly.

Fig. 3 is a section taken on line 3—3 of Fig. 1.

Fig. 4 is a section taken on line 4—4 of Fig.

3; and

Fig. 5 is a perspective view of a fastening or closure member which forms part of the improved model truck assembly.

Referring to the drawing, in which a preferred embodiment of the invention is shown, reference characters 5 and 6 designate the end frames of a model or miniature truck assembly for miniature railway cars, the end frames 5 and 6 being connected together at their centers by a bolster 7. The end frames 5 and 6 are provided with suitable recesses 4 in their ends to receive the ends of shafts 8 and 9 which have car wheels 10 mounted thereon.

The end frames 5 and 6 and the bolster 7 are preferably cast from soft metal such as ordinary white metal, and are preferably cast to reproduce to scale the similar parts of full-sized structures. Particular efforts are made to have the outer surfaces of the assembled model car truck appear to be true reproductions of the full-sized structures.

When the end frames, the bolster, the shafts and wheels have been assembled, the end frames must be free to adjust themselves somewhat independently of each other to accommodate for unevenness in the track or surface over which the model is to move, and the end frames must be held to a limited movement toward and away

from each other. To provide these features, the invention includes novel means for connecting the bolster 7 with the end frames 5 and 6. The bolster 7 is formed preferably with integral trunnions 15 which at their outer ends have integral disks 16. The disks 16 are disposed in pockets or recesses 17 provided in inwardly extending integral lugs 18 formed upon the end frames 5 and 6, the recesses or pockets 17 being open at their upper ends until closed by fastening or closure members 19 (Figs. 3, 4 and 5). It will be noted that the lugs 18 are provided with downwardly extending slots 20 through which the trunnions 15 project, the construction being such that the trunnions may rotate in the slots 20 and are slidably mounted therein. As best illustrated in Fig. 4, each of the lugs 18 is provided at its upper end with outwardly extending beads or ribs 22 to permit the associated closure or fastening member 19 to be attached to the lug so as to prevent accidental removal of the bolster from the associated end frame. The closure or fastening members 19 are preferably formed from sheet metal which is sufficiently elastic to permit the fastening members to be snapped on and off the lugs 18. It will be noted that each member 19 is formed with a lip or hook 23 at one end and with a lip or hook 24 at the other, which lip 24 is provided with an extension or finger piece 25 which may be grasped when it is desired to remove the member 19 from its lug 18. It is obvious that the lips or hooks 23 and 24 may be snapped on and off the beads 22.

As best shown in Figs. 3 and 4, there is sufficient space in the recesses or pockets 17 to permit movement of the bolster 7 upwardly and downwardly with respect to the end frames 5 and 6.

When the apparatus shown in the drawing is to be assembled, it is only necessary to assemble the wheels 10 with the shafts 8 and 9 and then assemble the shafts with the end frames 5 and 6, after which the bolster may be dropped in place between the frames and the fastening or closure members 19 may be snapped in place. The structure is then assembled and may be attached to a miniature car. For this purpose, the bolster is provided with a central bore 30 to receive a king pin (not shown).

While I have shown and described certain embodiments of my invention, it is to be understood that it is capable of many modifications. Changes, therefore in the construction and arrangement may be made without departing from the spirit and scope of the invention as dis-

closed in the appended claims, in which it is my intention to claim all novelty inherent in my invention as broadly as possible, in view of the prior art.

5 I claim:

1. A truck assembly for use in the construction of models of railway cars and the like having in combination, axles, car wheels on said axles, a bolster having trunnions at its ends and said 10 trunnions being provided at their outer ends with disks, end frames holding the ends of said axles and being provided with recesses opening at the top surfaces of said frames for said disks and of such size as to permit the disks to pass through the 15 openings for assembly of the structure, and closure members removably secured across the upper faces of said recesses to prevent accidental displacement of said disks from said recesses whereby said bolster is secured movably between said 20 end frames.
2. A truck assembly for use in the construction of models of railway cars and the like having in combination, axles, car wheels on said axles, a bolster having trunnions at its ends, said trunnions 25 having enlarged portions at their outer ends, end frames holding the ends of said axles, said end frames having recesses opening at the top surfaces of said frames for said enlarged portions and having slots for rotatably and slidably journaling said trunnions, and closure members 30 for said recesses to prevent accidental displacement of said enlarged portions from said recesses

whereby said bolster is secured movably between said end frames.

3. A truck assembly for use in the construction of models of railway cars and the like having in combination, axles, car wheels on said axles, 5 a bolster having trunnions at its ends and said trunnions being provided at their outer ends with disks, end frames holding the ends of said axles and being provided with recesses for said disks, and spring clips extending across above 10 said disks for closing said recesses to prevent accidental displacement of said enlarged portions from said recesses whereby said bolster is secured movably between said end frames, said spring clips being removably secured in position by means of 15 hook portions engaging beads on said end frames.

4. A truck assembly for use in the construction of models of railway cars and the like having in combination, axles, car wheels on said axles, a bolster having trunnions at its ends and 20 said trunnions having enlarged portions at their outer ends, end frames holding the ends of said axles, said end frames being provided with recesses for said enlarged portions and being provided with slots for rotatably and slidably journaling 25 said trunnions, and closure members snapped on said end frames over said recesses to prevent accidental displacement of said enlarged portions from said recesses whereby said bolster is secured movably between said end frames. 30

SIGURD BEUTLICH.
